(57) **CLAIM**

The ornamental design for the mine dewatering apparatus, as shown and described herein.

DESCRIPTION

FIG. 1 is a perspective view of the present invention depicting a first end of the mine dewatering apparatus;

FIG. 2 is a perspective view of the invention depicting a second end of the mine dewatering apparatus shown in FIG. 1;

FIG. 3 is a side view in elevation of the mine dewatering apparatus;

FIG. 4 is a side view in elevation of the invention as shown in FIG. 3, rotated 180°;

FIG. 5 is a side view in elevation of the invention as shown in FIG. 4, rotated 90° to the left; and,

FIG. 6 is a plan view of the invention.

1 Claim, 6 Drawing Sheets

FIG. 2

FIG. 3

FIG. 4

FIG. 5
